EARTH CARRYING SCRAPER

Albert R. Henry, Salina, Kans., assignor to Henry Manufacturing Co., Inc., Topeka, Kans., a corporation of Kansas

Application January 7, 1948, Serial No. 952

2 Claims. (Cl. 37—129)

1

This invention relates to new and useful improvements in scrapers, and has particular reference to a scraper adapted to be towed by a tractor or the like and to scrape up a load of earth, carry the load to any desired point, and there dump it.

A principal object of the present invention is the provision of a scraper comprising a yoke type draft means adapted to be towed by a tractor or the like, each of the arms of said yoke being pivotally connected at its rearward end to one corner of a vertically disposed triangular support plate, a ground engaging wheel carried for rotation at a second corner of each of said support plates; a bowl open at top and bottom carried pivotally between said support plates and supported thereby on an axis at the third corners thereof, a scraper pan carried for swinging movement within said bowl on said bowl axis and pivotally connected to said support plates at said draft axis, and powered means for moving said bowl longitudinally relative to said draft yoke, whereby said scraper pan may be tilted forwardly to lower its forward edge to a scraping position tilted rearwardly to a carrying position substantially enclosed within said bowl, and tilted still farther rearwardly to lower the rearward edge of the scraping pan beneath said bowl, thereby dumping the load of earth carried by said pan.

Another object is the provision, in a scraper of the class described having a bowl pivotally swung between the arms of a yoke type draft means, said bowl being movable longitudinally and vertically between said arms, of rollers carried for rotation on transverse axes by said bowl and projecting outwardly to be engaged in channels formed longitudinally in the arms of said yoke, whereby said bowl is maintained substantially upright regardless of the position of the scraper pan.

A further object is the provision, in a scraper of the class described having a bowl and scraper pan carried between outwardly spaced supporting wheels, of a digging member carried by said bowl and disposed behind each of said supporting wheels, said digging member being adapted to be lowered into the earth substantially simultaneously with the cutting edge of the pan, thereby cutting furrows in which said wheels may rest on the next pass of the scraper, the earth moved to form said furrows being moved inwardly into the path of said scraper pan.

Other objects are simplicity and economy of construction, and ease, dependability, and efficiency of operation.

2

With these objects in view, as well as other objects which will appear in the course of the specification, reference will be had to the drawings, wherein:

- 5 Figure 1 is a side elevation, partially broken away, of a scraper embodying the present invention, showing the bowl elevated and scraper pan in the dumping position.
- 10 Fig. 2 is a view of the parts shown in Fig. 1, with the bowl and scraper pan shown in the earth carrying position.
- 15 Fig. 3 is a view of the parts shown in Fig. 1, with the scraper pan and auxiliary discs shown lowered to the digging position.
- 15 Fig. 4 is a plan view of the scraper in the carrying position.
- Fig. 5 is an enlarged fragmentary vertical section taken on line V—V of Fig. 4.
- 20 Fig. 6 is an enlarged fragmentary vertical section taken on line VI—VI of Fig. 5.
- Fig. 7 is an enlarged fragmentary section taken on line VII—VII of Fig. 6.
- 25 Fig. 8 is an enlarged fragmentary section taken on line VIII—VIII of Fig. 5.
- Fig. 9 is an enlarged fragmentary section taken on line IX—IX of Fig. 5.
- 30 Fig. 10 is an enlarged fragmentary section taken on line X—X of Fig. 1, showing the supporting structure for one of the discs.
- Fig. 11 is an enlarged fragmentary section taken on line XI—XI of Fig. 10.
- Like reference numerals apply to similar parts throughout the several views, and the numeral 2 applies to a draft yoke comprising a pair of parallel spaced apart side arms 4 formed of inwardly opening channel irons, a cross-bar 6 extending between the forward ends of said side arms, a pair of spaced apart drawbars 8 rigidly connected at their rearward ends to cross-bar 6;
- 35 40 a brace 10 rigidly fixed to the forward end of each side arm 4 and extending forwardly and inwardly to join the adjacent drawbar 8 intermediate its ends; and a hitch plate 12 rigidly fixed between the forward end portions of drawbars 8. A clevis 14 is adapted to be pivotally connected to said hitch plate by means of a bolt 16 inserted selectively in any of a series of vertically spaced apart holes 18 formed therefor in said hitch plate, and is adapted to be connected at its forward end to a tractor or other towing means by means not shown.
- 45 45 As best shown in Figs. 6 and 7, each side arm 4 is pivotally connected at its rearward end to a tubular bushing 20 extending transversely to the scraper and being rigidly attached to a vertically

disposed planar support plate 22 adjacent one corner thereof, said support plates being substantially triangular in shape. Side arms 4 are disposed adjacent the inner surfaces of said support plates. A ground-engaging wheel 24 is carried for rotation on a stub axle 26 rigidly fixed to and extending outwardly from each of support plates 22 adjacent a second corner thereof, as shown in Figs. 1-4.

A substantially rectangular scraper bowl 28 open at top and bottom and having side walls 30, a curved forward wall 32, and a curved rear wall 34, is pivotally swung between support plates 22 by means of a pair of trunnion bolts 36, each of said trunnion bolts extending through a tubular bushing 38 rigidly attached to support plate 22 and through an outwardly extending tubular bushing 40 rigidly attached to the adjacent side wall 30 of the bowl, as best shown in Fig. 8. Side walls 30 are spaced inwardly from plates 22 sufficiently to swing freely between side arms 4 of yoke 2. Forward wall 32 and rear wall 34 of the bowl are reinforced by transversely extending angle irons 44 welded to the outer surfaces thereof along their lower edges.

A scraper pan 42 having side walls 46 and bottom 48 is swung within bowl 28, the side walls 46 of said pan being pivotally supported on trunnion bolts 36 and spaced apart from side walls 30 of the bowl by means of spacer washers 50 carried on said bolts, as shown in Fig. 8. A shaft 52 is carried for rotation in a plurality of bearing tubes 54 welded or otherwise securely fixed to the lower surface of pan bottom 48. Said shaft is disposed transversely to the line of travel of the scraper, and its extended end portions are carried rotatably in tubular bushings 20 fixed to support plates 22. A blade 56 is securely fixed to the forward edge of pan bottom 48 by bolts 58. Said pan bottom is reinforced by a plurality of longitudinally extending gusset plates 60 welded to the lower surface thereof, and the forward edge portions of pan side walls 46 are reinforced by strengthening plates 62 welded thereto. The forward edges of said side walls and said strengthening plates are bevelled outwardly to a sharp edge at 64 to permit the pan to be pulled easily through the ground.

Bar members 66 are welded or otherwise rigidly secured to the outer surfaces of the side walls 30 of bowl 28. Said bar members extend convergently inwardly at the forward end of the bowl. A piston rod 68 is pivotally connected at its rearward end between the forwardly extended ends of bars 66, and extends forwardly. At its forward end said piston rod carries a piston 70 slidably carried in a hydraulic cylinder 72 pivotally connected at its forward end to hitch plate 12 by means of pivot pin 74. Fluid under pressure may be introduced into cylinder 72 ahead of piston 70 by means of pipe 76 and flexible hose 78, and behind said piston by means of pipe 80 and flexible hose 82. Hoses 78 and 82 are interconnected with suitable pumping means not shown mounted on the tractor. Thus the piston may be moved to any position desired within the cylinder.

Referring particularly to Figs. 5 and 9, it will be seen that a transversely extending shaft 84 is carried in a mounting sleeve 86 welded or otherwise fixed to the outer surface of forward bowl wall 32 adjacent the lower edge thereof at each side of the bowl. Said shafts extend outwardly from each side of the bowl, and a tapered roller 88 is carried for rotation on the extended portion of each shaft. Said rollers project into and

are adapted to roll within the channel irons forming side arms 4 of draft yoke 2. As shown in Fig. 9, the legs of said channel have inner surfaces tapered to a degree substantially equal to the taper of the roller.

Referring to Figs. 1, 4, 10 and 11, it will be seen that a digging disc 90 is disposed immediately behind each ground-engaging wheel 24. As best shown in Figs. 10 and 11, each of said discs is mounted on an axle 92 carried for rotation in a bearing sleeve 94 rigidly mounted between substantially parallel side bars 96. Said side bars are pivotally connected adjacent their inner ends to bars 98, bars 98 being pivotally connected at their inner ends to ears 100 welded to reinforcing angle 44 fixed to the rearward end of bowl 28 by means of bolts 102, and extend outwardly and rearwardly therefrom. Side bars 96 are pivoted adjacent their inner ends to bars 98 by means of bolts 104.

Referring to Fig. 11, it will be seen that bars 96 are each provided with a transverse extending ear 106 provided with a series of spaced apart holes 108 through which bolts 110 may be selectively inserted to fix bars 96 to bars 98, thereby adjusting the angle of disc axle 92 relative to bars 98 and to the ground. Additional longitudinally spaced holes 112 and 114 are provided in bars 98 in which bolts 104 and 110 may be respectively inserted to adjust disc 90 longitudinally relative to bars 98. A rod 116 is pivotally connected at its lower end to an ear 118 fixed to one of bars 98, and extends upwardly and forwardly through a bracket 120 fixed to bowl 28. A stop collar 122 is fixed to the upwardly extended end of said rod. A coil spring 124 carried on said rod and adapted to be compressed between bracket 120 and a collar 126 fixed to said rod, is adapted to urge bars 98 resiliently downwardly.

The operation of the scraper is substantially as follows. With the parts having the relative positions shown in Figs. 2 and 5, fluid is delivered under pressure through hose 82 and pipe 80 to cylinder 72 behind piston 70, thus forcing piston rod 68 forwardly. This causes bowl 28 to be moved forwardly, turning about wheel axles 26 as an axis. Since trunnion bolts 36 carrying pan 42, move forwardly, and since pan shaft 52 is fixed relative to draft yoke 2, pan 42 tilts forwardly to bring blade 56 thereof into contact with the ground. Simultaneously bowl 28 is lowered, since it also is suspended from trunnions 36. However, the forward end of bowl 28, being guided relative to side arms 4 by rollers 88, is lowered at a slower rate than trunnion 36 is lowered, thus causing the forward end of the bowl to be tilted upwardly. This produces a rapid opening between blade 56 and the lower edge of bowl front wall 32.

The bowl and pan then have the relative positions shown in Fig. 3, the forward edge of the pan being lowered beneath the level of wheels 24 to dig a furrow or trough 128 in the earth. As bowl 28 is lowered, discs 90 are also lowered, and when the blade is fully lowered, the discs are lowered into the earth to cut a furrow in the earth behind each wheel 24, and to move the earth removed from said furrow into the trough cut by pan 42. In the usual scraper in which the wheels are spaced outwardly from the digging members, the wheels will support the digging members above the bottom of the trough on subsequent passes of the scraper. In this scraper, on the other hand, the furrows cut by discs 90 serve as tracks for wheels 24 when the scraper makes sub-

sequent passes, thus allowing the scraper pan blade to be lowered sufficiently to make a full cut. Furthermore, since the dirt removed from the furrows cut by discs 90 is moved into the trough cut by the pan, said dirt will be picked up and removed by the pan on its next subsequent pass.

When the scraper has been pulled forwardly with the blade lowered as in Fig. 3 to fill bowl 28 with earth, fluid is introduced under pressure through hose 78 and pipe 76 to cylinder 72 in front of piston 70, thus forcing the piston and piston rod 70 rearwardly with respect to draft yoke 2. This forces support plates 22 to rotate rearwardly about axles 26, thus raising bowl 28 as it is moved rearwardly. Since trunnion 36 is moved rearwardly with respect to pan shaft 52, pan 42 is tilted rearwardly. When the pan has tilted rearwardly sufficiently to be substantially enclosed within bowl 28 as shown in Figs. 2 and 5, the motion of piston 70 may be arrested and the earth transported as far as desired. When it is desired to dump the earth, piston 70 is moved still farther to the rear to tilt pan 42 still farther to the rear as shown in Fig. 1, thus dumping the earth over the rearward edge of pan bottom 48. Discs 90 are of course, elevated above the ground when bowl 28 is raised. Bowl 28 is at all times maintained substantially upright by the engagement of rollers 88 in side arms 4. The cycle may then be repeated as desired.

What I claim is:

1. A scraper comprising a pair of spaced apart parallel support members, an outwardly spaced ground-engaging wheel carried for rotation on a transverse axis by each of said support members at one corner of a vertically disposed triangle, a draft yoke having its straight arms pivotally connected to said support members on a transverse axis at a second corner of said triangle and extending forwardly, a unitary bowl open at top and bottom pivotally supported between said support members on a transverse axis at the third corner of said triangle, a roller carried for rotation by said bowl and adapted to engage a longitudinally formed track formed by the arms of said draft yoke, a scraper pan pivotally carried within said bowl on said bowl axis and pivotally connected to said draft axis, and powered means carried by said yoke for moving said bowl longitudinally relative to said yoke, whereby said

scraper pan may be tilted to bring its forward cutting edge into contact with the earth, tilted rearwardly to a carrying position substantially within said bowl, and tilted still farther rearwardly to a dumping position, said bowl being bodily elevated and maintained substantially upright as said pan is tilted rearwardly.

2. A scraper comprising a pair of spaced apart parallel support members, an outwardly spaced ground-engaging wheel carried for rotation on a transverse axis by each of said support members at one corner of a vertically disposed triangle, a draft yoke having its straight arms pivotally connected to said support members on a transverse axis at a second corner of said triangle and extending forwardly therefrom, a unitary bowl open at top and bottom pivotally supported between said support members on a transverse axis at the third corner of said triangle, and disposed between said yoke side arms, a roller carried for rotation on a transverse axis at each side of said bowl and adapted to project outwardly into guide channels formed longitudinally in the arms of said draft yoke, a scraper pan pivotally carried within said bowl on said bowl axis and pivotally connected to said draft axis, and powered means carried by said yoke for moving said bowl longitudinally relative to said yoke, whereby said scraper pan may be tilted to bring its forward cutting edge into contact with the earth, tilted rearwardly to a carrying position substantially within said bowl, and tilted still farther rearwardly to a dumping position, said bowl being bodily elevated and maintained substantially upright as said pan is tilted rearwardly.

ALBERT R. HENRY.
